UNITED STATES PATENT OFFICE.

JOHN L. GILCHRIST, OF WILKINSBURG, PENNSYLVANIA.

BUBBLE-PIPE.

1,330,701.

Specification of Letters Patent. Patented Feb. 10, 1920.

Application filed March 8, 1918, Serial No. 221,202. Renewed August 8, 1919. Serial No. 316,182.

To all whom it may concern:

Be it known that I, JOHN L. GILCHRIST, a citizen of the United States, residing at Wilkinsburg, in the county of Allegheny 5 and State of Pennsylvania, have invented new and useful Improvements in Bubble-Pipes, of which the following is a specification.

This invention relates to a bubble pipe 10 and has for its primary object to provide a pipe capable of supporting its own liquid and discharging the same in the necessary predetermined quantity to make successive bubbles.

15 An object of the invention is to construct a pipe to accomplish the foregoing results which may be cheaply manufactured and in which the parts are so associated that they may be disassembled and cleaned and 20 quickly reassembled by an unskilled person.

Besides the above my invention is distinguished in the novel manner of arranging the aperture and the stem so that atmospheric pressure may be reduced for allowing the flow of a predetermined quantity of liquid to a position to form a bubble and then atmospheric pressure increased for expanding the bubble.

With these and other objects in view the 30 invention will be better understood from the following detailed description taken in connection with the accompanying drawing wherein:—

Figure 1 is a vertical sectional view of 35 the pipe.

Fig. 2 is a horizontal sectional view.

Fig. 3 is a top plan view of the base.

My improved bubble pipe consists of a receptacle 1 stamped to have a depressed base 2 surrounded by a groove 3 that communicates with the interior of the receptacle. The base is formed with an aperture 4 of a size to accomplish a result hereinafter set forth. Frictionally engaging the 40 receptacle is a cap 5 for the purpose of making the interior of the receptacle air-tight. This receptacle is further provided with a ledge 6 upon which the soap 7 rests, should the same be of the proper rigidity, but if 45 found advantageous in practice wire gauze 8 may be supported upon the ledge and the soap upon the gauze.

Frictionally engaging the depressed base portion 2 is the correspondingly shaped end of a base 9 which for the sake of cheapness 55 may be made of wood. This base has formed therein a pair of cone shaped passages 10 communicating at their apex as indicated at 11. From this arrangement it will be seen that upon passage of liquid 60 from the receptacle through the aperture 4 the same will be fed toward the point 11 where the same will be held suspended due to the contraction of the passage at this point. Communicating with the passage 10 65 at a point directly below the aperture 14 is a stem 12 which may be of reed or rubber or other sanitary material.

In the initial uses of the pipe the water in the receptacle is agitated until a certain 70 amount of the soap is held in suspense in the water and when this takes place the pipe is ready to blow bubbles. To accomplish this latter operation it is necessary for the user to momentarily reduce atmospheric 75 pressure in that portion of the passage 10 adjacent the aperture 4 for compensating for the decrease in pressure within the receptacle 1 with a result that the required amount of liquid is discharged through the 80 aperture 4 and passed through the passage 10 to the point 11. When this takes place atmospheric pressure is increased in the passage 10 by the breath of the user and this increase in pressure causes the bubble 85 to be formed. I find from practical use of the pipe that this increase and decrease of air pressure adjacent the aperture 4 may be quickly changed for forming a series of bubbles such as when forming chain bubbles. 90

From the foregoing description taken in connection with the accompanying drawing it should be apparent that I provide a device admirably adapted for the purpose intended and which may be manufactured and sold at a comparatively low cost, with the advantage that the device is non-leakable.

Having described my invention what I claim is:

1. A bubble pipe comprising a receptacle 100 having a detachable top and its bottom depressed to form a recess there being an aperture in the bottom of the receptacle, a base frictionally engaging the walls of said

recess and provided with two cone shaped passages that communicate with each other at their apex and a stem arranged in the base and having an end thereof arranged 5 to one side of said apex.

2. A bubble pipe comprising a receptacle having its bottom depressed to form a recess with an aperture in the depressed portion, said receptacle being further provided

with a soap supporting ledge, a detachable 10 cap for the receptacle, a base frictionally engaging the depressed bottom portion of said receptacle and provided with a bubble passage and a stem communicating with said bubble passage. 15

In testimony whereof I affix my signature.

JOHN L. GILCHRIST.
